PANTY GIRDLE OR THE LIKE
 Paula Blatt, 1426 W. 3rd St., Cleveland Heights, Ohio
 Filed Jan. 17, 1961, Ser. No. 83,192
 1 Claim. (Cl. 128—528)

This invention relates to the general class of maternity garments and is for an improved girdle or panty-girdle.

One object of this invention is to provide such a garment with relatively fixed means for supporting engagement beneath the wearer's abdomen and with a front panel insert that is so constructed and arranged as to be free to stretch upwardly or vertically in response to the enlargement of the abdominal region during the period of pregnancy and without interfering with the supporting action of the means that engages beneath the wearer's abdomen.

Another object is to provide such a garment with an improved means of supporting engagement with the sacroiliac region of the wearer's body without interfering with the donning of the garment.

Other objects will appear from the following description and claim when considered together with the accompanying drawing.

FIG. 1 is a front elevation of the present garment in position upon the body of the wearer;

FIG. 2 is a side view thereof;

FIG. 3 is a rear view thereof;

FIG. 4 is a partial view illustrating the abdomen-supporting means.

It is to be understood that the present form of disclosure is merely for the purpose of illustration and that there might be devised various modifications thereof without departing from the spirit of my invention as herein set forth and claimed.

In the accompanying drawing the present invention is shown as being embodied in a panty-girdle although it might be embodied in a girdle also.

The garment, as herein illustrated, consists of a rear part 1 and a lower front part 2, both of which are of universally elastic material with greater stretch horizontally than vertically, and a front panel insert 3 of net or like material with universal stretch but with more pronounced stretch vertically of the garment. The seams between these several members are indicated by reference numerals 4 and 5 which occur approximately along the sides of the wearer's thighs. There is a longitudinally elastic band 6 at the top of the insert 3 and a wider longitudinally elastic band 7 at the top of the rear part 1. The crotch part is indicated by reference numeral 8 and each of the leg openings is provided with a longitudinally elastic band about the edge thereof, as at 9 and 10, with the usual garter attachments 11.

Upon the inside of the front panel 3 I have provided an abdomen-supporting means consisting of the lower longitudinally elastic member 12 of slightly arched form and an overlying upper longitudinally elastic member 13 of more pronounced inverted-arched form so as to ensure most efficient supporting engagement beneath the abdomen, these two members being sewn together and having their ends sewn in the seams 4 and 5 at the time of sewing the other parts together. The members 12 and 13 overlap each other to a greater degree from their ends towards the middle thereof and will provide most effective supporting engagement beneath the middle part of the abdomen, where most needed, as well as the sides thereof, and this laminated combination is entirely unattached and free except at the ends thereof. The member 12 may be of greater width than the member 13 so as to extend inwardly beneath the lower part of the abdomen

2

to sufficient extent for most efficient supporting engagement without danger of wrinkling. This abdomen-supporting means will remain in relatively fixed position while the panel insert 3 is free to stretch upwardly in response to the upward enlargement of the wearer's abdomen and without disturbing the position of the abdomen-supporting means 12—13 throughout the entire period of pregnancy. There is sufficient lateral stretch in the body of the garment to ensure snug engagement of the same about the region of the wearer's abdomen and buttock; and, with my present arrangement, there will be relatively independent action of the abdomen-supporting means 12—13 and the panel insert 3, respectively, so that the action of the one will not interfere with the action of the other during the progressive stages of pregnancy.

At the rear of the garment I have provided the reinforcing and supporting member 14 in the region of the sacroiliac joint of the wearer so as to further contribute to the wearer's sensation of security and comfort. This member 14 extends from the very top edge of the garment to a point substantially below the waist band and has only horizontal stretch as it is without stretch in the vertical direction. The lower part of this member 14 is of rectangular form but its upper part, in the area of the elastic waist-band, is of trapezoidal form so as to permit maximum stretch of the elastic waist-band and hence facilitate donning of the garment. With this arrangement, there is provided maximum upward supporting engagement in the sacroiliac region without interfering with the intended use of the garment.

Thus the abdomen-supporting means 12—13 and the upwardly elastic panel insert 3 may perform their respective functions relatively independently of each other; that is, the operation of the one will not interfere with the operation of the other throughout the progressive stages of pregnancy, thereby enhancing the combined sensation of security and comfort upon the part of the wearer. Also, the arrangement of the member 14 affords increased supporting engagement in the region of the wearer's sacroiliac joint in a most effective manner and without interfering with the donning of the garment. Furthermore, this garment may be made and sold at a popular price.

What I claim is:

A maternity garment comprising rear and side portions of elastic material and an abdominal-engaging panel insert with vertical stretch attached to and extending between said side portions, and a laterally extending longitudinally elastic abdomen-supporting means having two ends and arranged upon the inside of said insert and attached at only said two ends to said side portions of the garment, said abdomen-supporting means consisting of longitudinally elastic members secured together in overlying laminated relation to each other, to a substantial extent with said lamination gradually increasing from the ends towards the middle thereof and with said lamination adapted to extend beneath the wearer's abdomen in supporting engagement therewith, said abdomen-supporting means being otherwise unattached and free, whereby said vertically elastic insert may respond to the enlargement of the wearer's abdomen while said abdomen-supporting means remains in relatively fixed supporting engagement beneath her abdomen throughout the period of pregnancy.
